(57) **CLAIM**

The ornamental design for a bio-clamp with tamper-evident cover, as shown and described.

DESCRIPTION

FIG. 1 is a front/left side, perspective view of a first embodiment of a bio-clamp with tamper-evident cover;

FIG. 2 is a left side view thereof;

FIG. 3 is a right side view thereof;

FIG. 4 is a top view thereof;

FIG. 5 is a bottom view thereof;

FIG. 6 is a front elevational view thereof;

FIG. 7 is a rear elevational view thereof;

FIG. 8 is a front/left side perspective view of the second embodiment of the bio-clamp with tamper-evident cover;

FIG. 9 is a left side view thereof;

FIG. 10 is a right side view thereof;

FIG. 11 is a top view thereof;

FIG. 12 is a bottom view thereof;

FIG. 13 is a front elevation view thereof; and,

FIG. 14 is a rear elevation view thereof.

The broken lines depict portions of the article that form no part of the claimed design.

1 Claim, 14 Drawing Sheets
